UNITED STATES PATENT OFFICE.

CARROLL JOHNSON FARRAR, OF KIRKWOOD, GEORGIA, ASSIGNOR OF ONE-HALF TO
B. W. FARRAR, OF SUMMERTON, GEORGIA.

APPARATUS FOR SETTING RULE FORMS.

Application filed December 27, 1921. Serial No. 524,902.

To all whom it may concern:

Be it known that I, CARROLL J. FARRAR, a citizen of the United States, residing at Kirkwood, in the county of Dekalb and 5 State of Georgia, have invented new and useful Improvements in An Improved Apparatus for Setting Rule Forms, of which the following is a specification.

This invention relates to printing and 10 more especially to an improved method and apparatus for setting rule forms.

The old and prevailing practice of setting rule forms by hand, consists of setting standard type high printing rules and spacing 15 material, such as leads and quads. This practice is exacting, tedious and slow, and forms so set are rendered more or less inaccurate by accumulations or foreign matter such as ink and dust on the spacing material. Such inaccuracies often cause the 20 form to bind when locked into a chase, and consequent distorting of the rules and premature displacement of both rules and spacing material while on the press, which 25 may result in the entire form being pied.

A printed impression from a rule form inaccurately set shows the lines to be distorted and improperly spaced, particularly 30 where longitudinal and transverse lines should meet.

One of the objects of this invention is to provide a suitable base adapted to receive 35 and support, without compression, a series of rules, vertically disposed in operative position and in paralleled and spaced relation.

Further objects are to eliminate hand set spacing and materially reduce the time ordinarily required for work of this character, and to provide improved rules and devices 40 into which they may be set to insure absolute accuracy and afford perfect abutment of longitudinal and transversely set rules.

Further objects are to provide devices for setting rule forms which will prevent form 45 from binding, distorting and premature displacement of rules, and eliminate possibility of the form being pied.

With these and other objects in view, which will become apparent as the description proceeds, the invention resides in the construction, combination and arrangement of parts, hereinafter more fully described and claimed, and illustrated in the accompanying drawings, in which like characters

of reference indicate like parts throughout 55 the several figures, of which:

Figure 1 is a perspective view of a base having transverse rules set therein in accordance with the invention.

Figure 2 is a perspective view of a rule 60 for printing transverse lines.

Figure 3 is plan view of a complete form made up for printing and composed of several bases with rules set therein for printing transverse lines and standard type high 65 rules, set between bases for printing longitudinal lines and ready to be locked into chase in the usual manner.

Figure 4 is a perspective view of a form made up for printing and illustrates the 70 employment of several bases with rules for printing transverse lines set therein and standard type-high rules set between bases for printing longitudinal lines.

In reducing this invention to practice a 75 plurality of base members are employed into which the rules are set for printing transverse lines. The bases may be made from any suitable material, but preferably metal. Each base 5 is provided with a series of 80 transverse channels or grooves 6 terminating with enlargements 7 and adapted to slidably receive the rules 8 for printing transverse lines.

The rules 8 may be made from any suitable material but preferably brass, and in 85 such lengths as may be necessary to conform to the varied widths of the bases. The lower edges are thickened or enlarged as indicated at 9 and designed for a sliding 90 fit into the grooves in vertical and operative position as shown in Figure 1.

The height of the bases 5 and rules 8, and the depth of the grooves 6 are such that the 95 printing surface of the rules are type-high when set in the base in operative position.

The width and length of the bases 5 and the spaced relationship of the grooves 6 are varied to meet the requirements of the point and pica system of measuring and the number of bases required for a complete set is 100 reduced to the minimum by providing channels 6 in both upper and lower portion of each base.

In making up a complete form, such number and sizes of bases are employed as may be necessary for the desired size and standard type-high rules 10 are set between bases 105

for printing longitudinal lines. With the parts arranged as stated the form is ready for locking into chase in the usual manner for printing.

5. Although in the foregoing, certain elements may have been set forth as best adapted to perform the functions allotted to them, nevertheless, it is to be understood that various minor changes as to form, substance, 10 etc., may be resorted to within the scope of the appended claims without departing from or sacrificing any of the principles of this invention.

I claim—

15. 1. A reversible rule base having retaining means on opposite sides thereof adapted

to maintain rules engaged with one side spaced apart a distance greater or less than that maintained between rules engaged with the opposite sides.

2. A reversible compositor's rule base having rule retaining openings on opposite sides thereof, predeterminately spaced to meet requirements of the point and pica system.

3. A compositor's rule base having rule 25 retaining openings on opposite sides thereof adapted to maintain rules in operable position without the use of spacing material.

CARROLL JOHNSON FARRAR.
